Attorney.

UNITED STATES PATENT OFFICE.

ARTHUR JOHNSEN, OF SASKATOON, SASKATCHEWAN, CANADA, ASSIGNOR OF FORTY-FIVE PER CENT. TO JOHN ALEXANDER MACDONALD, OF DRUMHELLER, ALBERTA, CANADA.

BASE-SUPPORTED RAILWAY-RAIL JOINT.

1,400,291.

Specification of Letters Patent.

Patented Dec. 13, 1921.

Application filed November 2, 1920. Serial No. 421,418.

To all whom it may concern:

Be it known that I, ARTHUR JOHNSEN, a subject of the King of Great Britain, residing at the city of Saskatoon, in the Province of Saskatchewan, in the Dominion of Canada, have invented a new and useful Improvement in Base-Supported Railway-Rail Joints, of which the following is a specification.

- 10 My invention relates to improvements in a base supported railway rail joint, which is of that class in which the splice bars are drawn tightly against the rail by means of the rail joint base. This simple, strong and durable base supported railway rail joint is of such nature that it will hold the splice bars tight to the rail by means of the rail joint base when bolts which pass through the splice bars and the rails have worked loose.

I attain these objects by the methods illustrated in the accompanying drawings, in which:

Figure 1 is a plan showing the entire general arrangement of my railway rail joint. Fig. 2 is an enlarged vertical cross section of the same.

Similar letters refer to similar parts throughout the various views.

30 a and a^1 are a pair of rails, abutting together about the center of the base plate b . This base is rectangular in form, smooth and flush on its underside and provided with two converging slightly V shaped grooves C and C^1 formed in or on its upper surface. These grooves taper inwardly toward the upper edges as shown for the purpose of retaining the wedge shaped angle fish or joint plates d and d^1 in their correct position. The vertical flanges of these plates are the usual form fitting the sides and webs of the rails a and a^1 snugly and having the outer edges of their horizontal flanges formed to fit the V grooves C and C^1 in the base plate as shown. The base plate b is also provided with lugs b^1 and b^2 to take bolts e and e^1 passing therethrough, and through corresponding lugs d^2 and d^3 formed on the angle joint plates d and d^1 as shown in Figs. 1 and 2.

The operation of my device is as follows. The rails to be joined a and a^1 having been placed in position on the base plate b , the wedge shaped angle plates d and d^1 are placed in their grooves and forced forward thereby cramping the two rails rigidly to-

gether as if held in a vise. The whole is permanently and rigidly locked together by tightening up the bolts e and e^1 and made doubly secure by the insertion of the usual fish or joint bolts f and f^1-f^2 and f^3 . The holes in the angle plates to receive these bolts are elongated to allow for the longitudinal adjustment of the said angle bars.

I am aware that prior to my invention, splice bars were drawn tightly to the rail by means of bolts passing through the splice bars and the rail. I therefore do not claim such combination broadly; but

What I do claim as my invention and desire to secure protection by means of Letters Patent, is:—

1. In a rail joint, a base plate having a recess with longitudinally converging walls and bolt lugs, a pair of splice bars engaging the rails and flaring outwardly at their lower ends over the rail base into said recess and formed to wedge between said walls and said rails and having bolt lugs, and bolts through said bars and rail held by suitable nuts and bolts and nuts longitudinally drawing and holding said splice bars in said recess.

2. In a rail joint, a base plate having longitudinal ribs on the upper side forming converging walls for wedging operation and bolt lugs at each side at the outer end, rails having their ends meet on said plate between said walls, splice bars having flaring lower ends coating with said walls in wedging themselves to the rails and bolt lugs at the outer ends and bolts and nuts securing said splice bars and rails together and draw bolts and nuts assisting wedging operations and holding fast the bars and base.

3. In a rail joint, a base plate having a recess with longitudinally converging undercut walls and lugs on either side at the wide end of said recess, a pair of splice bars having flaring base portions forming wedges and dovetailed into said converging walls and having bolt lugs at the outer ends and elongated bolt slots, rails having their ends meet on said base, bolts and nuts for attaching the bars to the rails through said slots and bolts and nuts operating longitudinally in drawing the splice bars into the base recess and completing the wedging operation.

Edmonton, August 19th, 1920.
ARTHUR JOHNSEN. [L. S.]
